UNITED STATES PATENT OFFICE.

NICHOLAS JENKINS, OF WATERBURY, CONNECTICUT.

STIFFENING FABRIC FOR GARMENTS.

SPECIFICATION forming part of Letters Patent No. 396,820, dated January 29, 1889.

Application filed April 28, 1887. Serial No. 236,412. (No model.)

To all whom it may concern:

Be it known that I, NICHOLAS JENKINS, of Waterbury, in the county of New Haven and State of Connecticut, have invented a certain 5 new and useful Improvement in Fabrics Designed as Stiffeners for Clothing, of which the following is a specification.

Each stiffener is composed of horse-hairs or analogous elastic fibers applied together to 10 form a continuous cord, and saturated with a solution of india-rubber or analogous cementing material which allows the cord to bend. I have devised means for effecting this rapidly and certainly. This is inclosed by braiding 15 with cotton or analogous yarns, and treated with starch or analogous dressing and smoothed.

I work the stiffeners in a braiding-machine, and cover and unite them so that the fabric 20 shall be a series of such stiffeners applied together side by side, and connected by yarns of fibrous material extending transversely.

The following is a description of what I consider the best means of carrying out the invention:

The accompanying drawings form a part of this specification.

Figure 1 is a longitudinal vertical section through a portion of the apparatus employed 30 in the manufacture of a single stiffener before the covering is applied. The remaining figures are on a larger scale. Fig. 2 is a side view of a single stiffener partially covered. Fig. 3 is a cross-section on x - x in Fig. 2, on a 35 much larger scale. Figs. 4 and 5 are on the same scale as Fig. 2, and represent a number of the single stiffeners associated together by means of the covering. Fig. 4 is a cross-section, and Fig. 5 is a side view corresponding 40 to Fig. 4.

Similar letters of reference indicate corresponding parts in all the figures where they occur.

A is a series of gills or hackles. Horse-hairs 45 M' are supplied to these hackles, and are delivered therefrom in continuous strings or rovings M in the same manner as has long been practiced with hemp, manila, and other long straight fibers in the manufacture of 50 cordage.

B is a tank containing a thin solution of in-

dia-rubber dissolved in naphtha or other volatile solvent.

C D are a pair of rollers pressed gently together and turned by proper mechanism (not 55 represented) at a rate which corresponds with the movement of the partly-formed stiffener M. The upper roll, C, is of iron bare. The lower roll, D, has a core of iron and a cover of soft fabric. This roll runs in the dissolved 60 rubber and applies it to the horse-hairs M'. It wets their entire surfaces. The roving M, after being thus saturated, is led through a series of long and warm chambers, E, subject to active currents of air. On emerging with 65 the solvent evaporated the horse-hairs are bound together by the cementing-rubber, so as to make a reliable stiffener, which I will designate by the same letter, M, as before employed for the roving from which it is formed. 70 These stiffeners M are afterward carried through a braiding-machine, and covered by braiding on a series of cotton yarns, G. The cords or stiffeners M, composed of elastic fibers cemented together with yielding cement, may 75 be covered, each singly, as indicated in Fig. 2.

To make a broad fabric, using these stiffeners as component parts thereof, I apply a number of the stiffeners, M, in parallel positions, and cover by a braiding-machine arranged to 80 make a continuous tube of such size that on being cut open the material of the tube composed of these stiffeners, with cotton yarns G braided thereon, may be cut into the desired forms for corsets and other articles of dress 85 which require to be stiffened.

Fig. 4 is a horizontal section of the material in the act of being manufactured in a tubular form. It is not necessary to represent the braiding-machine for effecting this. Such are 90 common in other branches of the arts. The several stiffeners M are brought up through the several guides or "posts" of the braiding-machine arranged in a circle, and the bobbin-carriers perform their usual zigzag movements, traversing alternately inside and outside of the circle, one set of bobbins (not shown) traveling from right to left and the other set traveling from left to right.

The tube, after its completion and removal 100 from the machine, is cut open by hand or machinery and the material extended and flat-

tened, after which it may be cut in goring or other forms, and united by sewing.

Modifications may be made in the details. The completed fabric may be sized and smoothed by ordinary means to give a finished surface.

I can use boiled linseed-oil partially or completely oxidized, gutta-percha, or various other tough and yielding material as substitutes for the rubber. It is important that it be a yielding cement of sufficient strength and adapted to endure the conditions to which clothing is subjected. I consider all such cements equivalents of rubber.

I can use the horse-hairs M' either of the full marketable length—such as are used for weaving horse-hair cloth—or the shorter hairs, which, being unfit for cloth, are of much less value. I can mingle elastic vegetable fiber with the horse-hairs. I believe some success may be attained by the use of tampico or anal-

ogous stiff vegetable fiber of proper size and length without horse-hairs. It is important that the fibers M' be strong and elastic and adapted to be coated and cemented together. 25

I claim as my invention—

The fabric described composed of a series of compound stiffeners of horse-hair or analogous elastic filaments and rubber, each of said compound stiffeners being covered, and the 30 stiffeners of the series united by a covering of cotton or analogous yarns, G, extended across from one compound stiffener to the next, forming the fabric, as herein specified.

In testimony whereof I have hereunto set 35 my hand, at Waterbury, Connecticut, this 21st day of April, 1887, in the presence of two subscribing witnesses.

NICHOLAS JENKINS.
